Filed July 14, 1972, Ser. No. 271,891

Term of patent 14 years

Int. Cl. D6—99

U.S. Cl. D6—45

FIG. 1

FIG. 2

FIG. 3

FIG. 4

FIG. 1 is a perspective view of a combined table and seat unit showing my new design;

FIG. 2 is a top plan view thereof as viewed in FIG. 1;
 FIG. 3 is a front elevational view of FIG. 1; and
 FIG. 4 is an end view of FIG. 1.

The characteristic feature of my design resides in the particular configuration and appearance of the seat members in combination with the top.

I claim:

The ornamental design for a combined table and seat unit, as shown.
